EXHAUST STEAM INJECTOR

Emanuel Rawson, North Bergen, N. J., assignor to
The Superheater Company, New York, N. Y.

Application February 8, 1933, Serial No. 655,710

4 Claims. (Cl. 103—265)

My invention relates to exhaust steam injectors and aims to provide an arrangement adapted to increase the commercial efficiency of such devices.

Commercial exhaust steam injectors employ not only exhaust steam, but also supplementary live steam. Such supplemental steam is necessary to maintain the device in operation under certain conditions encountered in average practice; but under certain operating conditions, it is possible to employ more exhaust steam and less supplemental live steam than under other conditions. Of course, the less live steam and the more exhaust steam used the greater are the fuel and water savings of the steam generating apparatus supplied by the injector. The savings thus indicated are at present only slightly available, if at all.

It is an object of my invention to provide an arrangement whereby the total amount of supplemental live steam used may be considerably reduced as compared with that required with present arrangements.

In order that my invention, together with its objects and advantages, may be fully and readily understood, I will now describe in detail and in connection with the accompanying drawing, apparatus for use with an exhaust steam injector for the purpose stated, this apparatus being selected by way of example from a number of possible embodiments of my invention. In the drawing:

Fig. 1 is an elevational view of apparatus embodying my invention.

Fig. 2 is a fragmentary detail in section on an enlarged scale of a portion of an apparatus similar to that illustrated in Fig. 1, but including some additional features.

In the drawing, 10 indicates as a whole an injector apparatus of a known type having nozzles, not shown, for utilizing exhaust steam and the required amount of supplemental live steam. In the arrangement shown, exhaust steam is conducted to the injector by the pipe 12 and supplemental live steam is conducted to injector 10 by pipe 14. Auxiliary live steam to take the place of exhaust steam, when such is not available, is brought to injector 10 by pipe 16. Feed-water is supplied to the injector 10 through the pipe 18 and the pipe 20 serves to convey the discharge from the injector to the boiler. The usual overflow pipe is shown at 22.

The live steam supplied through pipe 14 is at substantially constant pressure throughout the major portion of the time the apparatus is in op-

eration. In the ordinary arrangement such supplemental steam passes directly to a nozzle of constant orifice opening, so that the flow of live steam is substantially constant irrespective of other conditions of operation of the injector. The pressure of exhaust steam supplied through pipe 12, however, varies widely. For instance, while the average exhaust steam injector is designed to operate on exhaust steam pressures even lower than one-half pound per square inch gauge, the pressure of exhaust steam frequently runs above 15 pounds. The nozzle for the supplemental steam, however, must be designed to maintain the injector in operation at some definite lower limit of exhaust steam pressure. At all pressures above such lower limit, enough exhaust steam is available so that the injector would remain in operation and function satisfactorily if the supply of live steam were reduced and a greater amount of exhaust steam could then be utilized to increase the fuel saving.

The foregoing discussion as to exhaust steam and live steam has assumed that the temperature of the feed water has remained constant. This is not true under all operating conditions, however, where water temperatures often fluctuate over a very wide range. It so happens that the amount of supplemental live steam required by the injector increases with increase of temperature of the feed water.

Briefly stated, the apparatus herein disclosed provides automatic means whereby the supply of supplemental live steam to the injector 10 is decreased upon increase of pressure of exhaust steam supply and increased upon increase of temperature of the feed water supply. However, I do not limit myself to the use of both such automatic means in a given apparatus. At times I may employ one without the other.

In the arrangement illustrated for regulating the supply of supplemental live steam, I have provided a double seat valve 24 (Fig. 2) in valve chamber 26. Valve 24 has a stem 28 which extends through the casing 26. 30 is an expansible chamber preferably of the ordinary sylphon type formed of a cylinder of thin corrugated metal, one end of which is free but closed and the other is closed and fixed to a stationary support 32. The outer end of valve stem 28 is secured to the free end of chamber 30. The interior of the chamber 30 contains exhaust steam at the pressure existing in the pipe 12, such steam being conducted to chamber 30 through support 32 by means of pipe 34. As is evident from Fig. 2, an increase in the pressure of the exhaust steam will expand

the bellows-like chamber 30, causing its free end to push against rod 28 in a direction tending to close valve 24 and therefore to cut down the supply of supplemental live steam to the injector 10. 5 Spring means are provided so that whenever the pressure of exhaust steam in pipe 12 decreases such spring means tends to contract the chamber 30 to draw the valve stem 28 in the direction to open the valve 24.

10 The means whereby the temperature of the water supply varies the supplemental live steam to injector 10 may very conveniently also be associated with the valve stem 28. In the arrangement shown, a thermostat member 36 is placed 15 in the pipe 18 for the water supply to injector 10. Member 36 is of a known type of thermostat containing a liquid boiling at a low temperature and member 36 is connected by pipe 38 to a second sylphon chamber 40. When the temperature of 20 the water in pipe 18 rises, the increase in pressure of the liquid within member 36 is transmitted through pipe 38 to the interior of chamber 40. Chamber 40 is shown as mounted on the same support 32 as chamber 30. Motion of the 25 free end of chamber 40 caused by changes in pressure in the pipe 38 are transmitted to the valve stem 28 through a lever 42 which is pivoted intermediate its ends to a fixed support 44 and has its one end pivoted to the stem 28 and its other 30 end pivoted to a projection or stem 46 which is connected in turn to the free end of the sylphon chamber 40. It will be seen that an increase in pressure in chamber 40 tends to expand it and to open the valve 24, such action being resisted 35 by the spring means referred to above.

As illustrated in Fig. 2, such spring means comprises springs 48 and 48a. Spring 48 rests at one end upon an abutment 49 and presses at its other end against the end of stem 46. Spring 48a rests at one end against a portion of casing 26 and at the other end against a ring 50 fixed to stem 28. Springs 48 and 48a are preferably so chosen that valve 24 assumes a mean position when the pressure of exhaust steam in pipe 12 45 is at its mean value and the temperature of feed water in pipe 18 also is at its mean value. As the pressure of exhaust and/or the temperature of the feed varies, the position of valve 24 is automatically shifted by the expansion and/or 50 contraction of chambers 30 and 40 so as to permit the flow through such valve of the optimum amount of live supplementary steam for the injector 10. While the resiliency of chambers 30 and 40 tends to assist the action of springs 48 and 48a, the spring action of such chambers is 55 usually slight and difficult to predict. Therefore the spring means preferably is sufficiently stiff so that the resiliency of the walls of chambers 30 and 40 has a negligible effect on the position of valve 24. Preferably, also, both spring 48 and spring 48a are used, but I do not limit myself to this, the arrangement of Fig. 1 having only the spring 48. When only one spring is used, it, of course, must have one end fastened to the abutment and the other end fastened to the movable member so as to act in tension as well as in compression. Preferably also the stem 28 of

5 valve 24 contains a means of adjustment. Such a means is illustrated as a threaded joint at 28A (Fig. 2) and a jam nut 29 to hold the valve in adjusted position. The position of valve 24 at the time the chambers 30 and 40, or either of them, are in their mean positions can be determined to obtain the optimum results in operation. In Fig. 1, however, the joint at 28A has been omitted.

The actual position of valve 24 will, in use, 10 evidently be determined by the exhaust pressure and by the temperature of the feed water as it arrives at the injector. The amount of live steam is cut down in proportion as the pressure of the exhaust steam and the temperature at the feed 15 water make this possible thereby avoiding the wasteful use of high pressure live steam.

When the water temperatures do not fluctuate much, the regulation in accordance with fluctuations in this temperature may be omitted; and 20 conversely when conditions are such that these water temperatures vary but the exhaust steam pressure is substantially constant, the means for regulating in accordance with the pressure variations may be omitted.

25

What I claim is:

1. The combination with an injector having a live steam supply, an exhaust steam supply, and a water supply, of a valve adapted and arranged to vary the flow from said live steam supply to 30 the injector, means for applying a force in the direction to close said valve upon increase in pressure of said exhaust steam supply, and means for applying a force in the direction to open said valve upon increase in temperature in said water 35 supply.

2. The combination with an injector of a live steam supply, an exhaust steam supply, a water supply, a valve adapted and arranged to vary the flow from said live steam supply to the injector, and means for applying a force in the direction to open said valve upon increase in temperature of water in said water supply.

3. The combination with an injector of a live steam supply, an exhaust steam supply, a water 45 supply, a valve adapted and arranged to vary the flow from said live steam supply to the injector, a stem for said valve, an expansible chamber connected to said stem, a connection from said chamber to said exhaust steam supply, a 50 lever pivoted intermediate its ends, a pivoted connection from said lever to said valve stem, a second expansible chamber, a projection fixed to said second chamber, a pivoted connection between said lever and said projection, and means for decreasing and increasing the pressure in said second chamber with increase and decrease of the temperature of said water supply.

4. The combination with an injector of a live steam supply, an exhaust steam supply, a water 60 supply, a valve adapted and arranged to vary the flow from said live steam supply to the injector, combined spring and thermostatic means for applying a force in the direction to open said valve upon increase in temperature of water in 65 said water supply.

EMANUEL RAWSON.
